UNITED STATES PATENT OFFICE

WALTER LAMPL, OF NEW YORK, N. Y.

COMBINED NECKLACE AND BROOCH

Application filed January 6, 1928. Serial No. 244,978.

The present invention relates to improvements in neck and dress ornaments usually worn by women.

An object of the invention is the provision of a duplex ornament which when the parts thereof are assembled may be worn as a necklace and when the said parts are separated one of the same may be worn as a brooch.

10 A further object of the invention is the provision of a separable fastener which is ideally adapted as a means for connecting a string of beads or the like to a brooch whereby the said string and brooch may constitute 15 a necklace, and which is further adapted for connecting the brooch to a pin fastener or the like and allow the same to be worn as a dress ornament.

The above and other objects are accomplished by instrumentalities pointed out in the following specification.

The invention is clearly defined in the claims.

A satisfactory embodiment of the invention is illustrated in the accompanying drawings forming part of the specification and in which

Fig. 1 is a front elevation of a necklace provided with the device of the present invention;

Fig. 2 is a rear elevation of a section broken from the lower portion of Fig. 1 and showing in full elevation one form of the present device;

Fig. 3 is an enlarged detail cross section on the line 3-3 of Fig. 2 looking in the direction of the arrows;

Fig. 4 is a view similar to Fig. 3 and taken on the line 4-4 of Fig. 3 showing one of the beads separated from the socket;

Fig. 5 is a detail perspective of a modified form of bead; and

Fig. 6 is a view similar to Fig. 3 showing the bead illustrated in Fig. 5 forming part 45 of the brooch.

In the drawings *a* indicates a necklace made up of a string of beads 5 and a brooch 6. These parts may be of any desired construction, type or style. The rear face of 50 brooch 6 is provided with the usual metallic

plate or frame 7 which in the present instance forms part of the conventional setting for the carved stone 8.

The separable fastener which is employed for connecting brooch 6 to the ends of string 5 comprises a metallic body portion 9 disposed transversely of frame 7 and having a double or open ended longitudinal socket 10 adapted for receiving the heads 11-11 forming the terminal portions of string 5. The heads are endwise insertable into the opposite ends of socket 10 formed with a slot 21. When the said heads 11-11 are within socket 10 accidental outward displacement of the heads is prevented by latch and keeper constructions indicated generally and respectively by 12 and 13. The heads 11-11 are of flat metallic strips. In the present instance these strips are resilient and the latches 12 may be conveniently provided by bending 60 each strip upon itself and adjacent the intermediate portion thereof to provide limbs of unequal lengths. As viewed in Fig. 3, the shorter of the said limbs is the lower and indicated by 14 and its free end portion curves outwardly from the adjacent limb 15. The keepers 13 are in the form of upstanding flanges at the opposite ends of body 9. The entrance openings to the slotted socket 10, between the top plate 16 of the socket and the keepers are of sizes to nicely receive the free or bent end portions of the terminals 11-11. When inserting the said terminals the limbs 14 are arranged in contact with the keepers 13 so that the latter operate to deflect the curved free end portions of the limbs 14 as these override the keepers. When the said curved free end portions move inwardly and beyond the keepers, the limbs 14 move to their normal positions and behind 75 the keepers so that the latter prevent outward movement of the heads from the socket. Relatively thin angular shaped extensions 17-17 of the limbs 14, extend outwardly from the free ends thereof and notches 18 are provided in the keepers 13 to receive the inner side portions of the extensions 17-17 as the limbs move outwardly within the socket and into the positions shown in Fig. 3.

When removing the heads from the socket 80 85 90 95 100

the outer end portions of extensions 17 are manipulated to flex the limbs 14 inwardly until the free curved end portions are clear of the keepers whereupon an outward pull applied to the heads detaches the same from the socket. The outer ends of the limbs 15 are provided with transverse plates 18 rigidly secured thereto and of sizes to provide closures for the open ends of socket 10. The 10 said plates provide stops and limit inward movement of the heads into the sockets by abutting the ends of body 9 when the limbs 14 move behind the keepers 13.

In the form shown in Fig. 6 the head 19 15 conforms in length to the length of socket 10 and is endwise insertable into one end of the socket. A pin clasp 20 is carried by the head, and top plate 16 of body 9 is longitudinally recessed as at 21 to receive the pin clasp. 20 The recess 21 as shown opens through one end of said top plate 16. Except for the presence of pin clasp 20, and the length of head 19, the latter is constructed identical to heads 11-11 as shown.

25 From the foregoing description the use of the device will be readily understood, it being obvious that when the heads 11-11 are detached from the brooch and the head 21 inserted into the socket 10, as shown, the brooch may be readily worn as a dress ornament.

Although I have shown and described an ideal embodiment of the invention, it is obvious that the same is susceptible of various 35 modifications, and I reserve the right to the use of these as may come within the scope of the appended claims.

What I claim is:

1. A brooch forming one element of a 40 separable fastener, said brooch having a socket open-ended at one end and provided with a slot extending longitudinally of the brooch, said slot being open-ended at said open end of the socket, said socket being dimensioned for receiving a pair of heads forming another element of the fastener, and the terminals of a necklace, said open-ended slot being constructed for receiving a single head when the first named heads are removed from the socket, said single head having means for attaching the same to a garment.

2. A brooch forming one element of a 45 separable fastener, said brooch having a socket open-ended at one end, and provided with a slot extending longitudinally of the brooch, said slot being open-ended at said open end of the socket, the opposite end of said socket having an opening, keepers located within said socket respectively adjacent said open end and said opening, said socket being constructed to receive a pair of heads forming another element of the fastener, and the terminals of a necklace and 50 insertable into the opposite ends of said

socket, said heads having manually operable means cooperating with the keepers to prevent outward movement of the heads, said open-ended slot being constructed to receive a single head similar to the first named heads 70 upon removal of the latter from the socket, said single head having means for attaching the same to a garment.

3. A brooch forming one element of a 75 separable fastener, said brooch having a socket open-ended at one end, and provided with a slot extending longitudinally of the brooch, said slot being open-ended at said open end of the socket, the opposite end of said socket having an opening, keepers 80 located within said socket respectively adjacent said open end and said opening, said socket being constructed to receive a pair of heads forming another element of the fastener and the terminals of a necklace and 85 endwise insertable into the opposite ends of the socket, said heads having resilient latches for cooperating with the keepers to prevent outward displacement of the heads, said open-ended slot being constructed to receive a single head when the first named heads are 90 removed therefrom, said single head having a resilient latch cooperating with one of said keepers, and further having means for attaching the said head to a garment.

4. A brooch forming one element of a 95 separable fastener, said brooch having a socket open-ended at one end, and provided with a slot extending longitudinally of the brooch, said slot being open-ended at said open end of the socket, the opposite end of said socket having an opening, keepers located within said socket respectively adjacent said open end and said opening, said socket being constructed to receive a pair of heads forming another element of the fastener and the terminals of a necklace and 100 endwise insertable into the opposite ends of the socket, said heads having stops for limiting movement thereof into the sockets, and further having resilient latches for cooperating with the keepers to prevent outward displacement of the heads, said open-ended slot being constructed to receive a single head when the first named heads are removed 105 therefrom, said single head having a resilient latch cooperating with one of said keepers, and further having means for attaching the said head to a garment.

5. A brooch forming one element of a 110 separable fastener, said brooch having a socket open-ended at one end, and provided with a slot extending longitudinally of the brooch, said slot being open-ended at said open end of the socket, the opposite end of said socket having an opening, keepers located within said socket respectively adjacent said open end and said opening, said socket being constructed to receive a pair of heads forming another element of the fastener and the 115 terminals of a necklace and insertable into the opposite ends of said 120 socket.

5 terminals of a necklace and endwise insertable into the opposite ends of the socket, said heads having stops for limiting movement thereof into the sockets, and further having resilient latches for cooperating with the
10 keepers to prevent outward displacement of the heads, said open-ended slot being constructed to receive a single head when the first named heads are removed therefrom,
15 said single head having a resilient latch cooperating with one of said keepers, and further having means for attaching the said head to a garment, together with a stop for limiting movement of said single head into said socket.

Signed at New York city, in the county of New York and State of New York, this 28th day of December, A. D. 1927.

WALTER LAMPL.
